(57) **CLAIM**

The ornamental design for a display screen with graphical user interface, as shown and described.

DESCRIPTION

The FIGURE is a front view of a display screen with graphical user interface showing the new design.

The design consists of the ornamental features of screen displays, etc., as shown in solid lines of the FIGURE. The broken lines showing text, graphical elements, and the display screen are for environmental purposes only and form no part of the claimed design.

The article in which the design is embodied is a graphical user interface for a laboratory instrument such as a microplate reader.
